(57) **CLAIM**

The ornamental design for a notebook computer, as shown and described.

DESCRIPTION

FIG. 1 is a perspective view of a notebook computer showing a first embodiment of our new design;

FIG. 2 is a front view of the first embodiment;

FIG. 3 is a rear view of the first embodiment;

FIG. 4 is a left side view of the first embodiment;

FIG. 5 is a right side view of the first embodiment;

FIG. 6 is a top view of the first embodiment;

FIG. 7 is a bottom view of the first embodiment;

FIG. 8 is a perspective view of the first embodiment, shown in closed state;

FIG. 9 is a perspective view of a notebook computer showing a second embodiment of our new design;

FIG. 10 is a front view of the second embodiment;

FIG. 11 is a rear view of the second embodiment;

FIG. 12 is a left side view of the second embodiment;

FIG. 13 is a right side view of the second embodiment;

FIG. 14 is a top view of the second embodiment;

FIG. 15 is a bottom view of the second embodiment;

FIG. 16 is a perspective view of the second embodiment, shown in closed state;

FIG. 17 is a perspective view of a notebook computer showing a third embodiment of our new design;

FIG. 18 is a front view of the third embodiment;

FIG. 19 is a rear view of the third embodiment;

FIG. 20 is a left side view of the third embodiment;

FIG. 21 is a right side view of the third embodiment;

FIG. 22 is a top view of the third embodiment;

FIG. 23 is a bottom view of the third embodiment; and,

FIG. 24 is a perspective view of the third embodiment, shown in closed state.

The broken line portions of the notebook computer in all views represent unclaimed portions of the claimed design and form no part thereof.
